UNITED STATES PATENT OFFICE.

AMBROSE VINCENT KELLY, OF BROOKLYN, NEW YORK.

FIREPROOF DOOR.

1,408,302.

Specification of Letters Patent. Patented Feb. 28, 1922.

Application filed January 14, 1921. Serial No. 437,388.

To all whom it may concern:

Be it known that I, AMBROSE V. KELLY, a citizen of the United States, and a resident of the city of New York, borough of Brooklyn, in the county of Kings and State of New York, have invented a new and Improved Fireproof Door, of which the following is a full, clear, and exact description.

The present invention relates to new and useful improvements in sliding doors and it pertains more particularly to doors of this character commonly known as "fire doors" and used between the compartments in fire-proof buildings. Doors of this type are generally maintained in open position by means of counter weights or similar devices controlled by fusible links, said doors being mounted upon an inclined track in order that they may automatically move to closed position upon operation of the fusible link. In doors of the type just described, however, great difficulty is experienced in opening the same since such doors in order to properly perform their functions, must necessarily be constructed from heavy material, and owing to the inclined track the operation of moving the heavy doors up the incline of the track is not easily accomplished.

It is one of the objects of the present invention to so mount these doors that they may be moved along a true horizontal track with little effort.

It is a further object of the invention to so construct the track on which the doors are mounted that the same is automatically moved to an inclined position in order that the door may automatically close.

In constructions as above mentioned it is obvious that when the track is in the true horizontal position, the bottom edge of the door must necessarily be spaced with relation to the floor of the building, and it is a further object of the invention to provide means which will close the space between the bottom edge of the door and the floor of the building, and, at the same time, will permit of free and easy operation of the door.

With the above and other objects in view, reference is had to the accompanying drawings, in which

Figure 1 is a front elevational view, partly in section, of a door opening and door constructed in accordance with the present invention;

Fig. 2 is a vertical sectional view taken on the line 2-2 of Fig. 1, and

Fig. 3 is a detail vertical sectional view taken on the line 3-3 of Fig. 1.

Referring more particularly to the drawings, the reference character 5 designates a door opening, and 6 represents the door which is adapted to close the opening. The door 6 has its upper edge inclined as indicated by the reference character 7, and secured to said upper edge are door hangers 8, said hangers being fastened to the door by means of bolts 9. These hangers 8 each carry rollers 10, and said rollers are adapted for rolling engagement upon a track 11.

The track 11 is pivotally mounted at its rear end, as indicated by the reference character 12, and is adapted to swing to the dotted-line position shown in Fig. 1, in which position its forward end is supported by means of a bracket or the like 13.

For supporting the track 11 in the true horizontal position shown in full lines in Fig. 1, a trigger 14 is pivotally mounted as at 15, and said trigger comprises two rigid arms 16 and 17. The trigger 14 is maintained in the position shown in Fig. 1, by means of a cord or the like 19, secured at one end, as at 18, to the arm 17 of the trigger, the other end of said cord 19 being provided with a ring 20 adapted to be received by a hooked member 21. This cord 19 passes around a pulley 22, and interposed on the cord at a suitable point between its ends is a fusible link 24 of any suitable nature.

Rigidly secured to the wall adjacent the free end of the track 11, by suitable fastening means 23, is a guide member 24, and said guide member 24 is adapted to guide the free end of the track 11.

Mounted in brackets 30' above the track 11, is a supplemental track 25, and mounted on said track 25 are rollers 26 carried by hangers 27. Depending from each of the hangers 27, is a rod 28 and rigidly secured to the lower ends of said rods as at 29, is a pan-like structure 30, which pan-like structure is adapted to receive the lower edge of the door 6. These rigid rods 28 are secured to the pan-like member 30 in such a manner that the member 30 will be supported just out of contact with the floor in order that it may travel with the door as the latter moves to open and closed position.

With the parts in the position shown in Fig. 1, if it is desired to close the door, the

same need only be moved along the track 11 to the closed position, and owing to the true horizontal plane of said track the door will remain in any position in which it may be placed, that is, completely open, completely closed, or only partly closed. If, however, the door is open, as shown in Fig. 1, an automatic closing thereof would be effected by a fusing of the fusible link 24, which fusible link 24 serves to part the cord 19. As the cord 19 parts, the support for the trigger 14 is destroyed, and said trigger rocks about its pivotal point 15 to the position shown in dotted lines in Fig. 1 and permits the track 11 to fall to rest upon the bracket 13, as shown in dotted lines in Fig. 1. When the track 11 has fallen to the position shown in dotted lines, it will be apparent that the door will travel down the incline to closed position until it engages the brackets 31 where it will be retarded. Owing to the door 6 being received within the pan-like member 30, it will be apparent that as the track 11 drops to the lower position, the door will move downwardly into the pan-like member 30, and as the door travels to closed position by reason of the engagement of its forward edge with the forward end of the pan-like member 30, the latter will be moved with the door in order that the space between the bottom edge of the door and the floor may at all times be substantially filled.

What is claimed is:

- 35 1. In a device of the character described, a door, a pivoted track, means for supporting the track in true horizontal position, and means for releasing the support of said track to permit the same to automatically assume an inclined position in order that the door may automatically move therealong to closed position.
- 40 2. In a device of the character described, a door, a pivoted track for supporting the same, and fusible means for supporting one end of said pivoted track normally in a true horizontal plane.
- 45 3. In a device of the character described,

a door, a pivoted track, a pivoted trigger member adapted to support the track in a true horizontal plane, and fusible means adapted to maintain said trigger in track-supporting position, said fusible means being adapted to release the track-supporting trigger and permit of the track moving to inclined position to effect an automatic movement of the door along the track.

4. In a device of the character described, a door, a pivoted track, means for automatically releasing said track to provide for an automatic movement of the door therealong, and means for closing the space between the bottom edge of the door and the bottom edge of the door opening with which the door is adapted to coact.

5. In a device of the character described, a door, a pivoted track, a fusible link adapted to automatically release said track to provide for an automatic movement of the door therealong, a supplemental track, and means supported by said supplemental track and movable by the door for closing the space between the bottom edge of the door and the door opening with which the door is adapted to coact.

6. In a fire door, in combination with a door opening, a track pivoted at one end, a door carried upon said track, means for supporting the free end of said track, and a fusible link in said supporting means whereby upon the fusing of said link the track is permitted to assume an inclined position to permit of a movement of the door therealong by gravity.

7. In combination with a door opening, a self-closing door comprising a track pivoted at one of its ends and adapted to normally occupy a true horizontal plane, and fusible means connected in said supporting means whereby upon fusing of the fusible means the track automatically assumes an inclined position to permit of free movement of the door therealong under the influence of gravity.

AMBROSE VINCENT KELLY.
